Attorney.

UNITED STATES PATENT OFFICE.

JOHN N. HELTZEL, OF WARREN, OHIO.

CONCRETE FORM.

Application filed December 3, 1925. Serial No. 72,961.

The present invention relates to concrete forms, and aims to provide a novel and improved form to facilitate the construction of concrete slabs or sections having a space between them, for the purpose of receiving a bituminous, concrete or other suitable filler so as to provide a sealed joint, and, if desired, a traffic line between the slabs, this invention being an improvement over the collapsible forms disclosed in my copending application Serial No. 718,376, filed June 6, 1924.

Another object of the invention is the provision of a simple and inexpensive form to be used at one side or edge of a completed concrete slab, to define the adjacent side or edge of another slab or section under construction, in order that said slabs will be spaced apart.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a perspective view of one of the forms in place, showing the slabs in section.

Fig. 2 is a perspective view of the form removed, showing an implement used for withdrawing the form from between the slabs.

Fig. 3 is an end view of the form showing the slabs in section.

Fig. 4 is a perspective view illustrating a modification.

The form comprises a vertical plate 10 of suitable length, and of suitable sheet metal, having at its upper edge a horizontal flange 11 extending to one side. The plate 10 is of a height equal to the depth of the concrete road or other surfacing structure for which the form is used, and the flange 11 is of a width greater than the space to be produced between the slabs or sections.

The plates 12 and 13 are riveted or otherwise secured to that side of the plate 10 below the flange 11, and have the curved leaf springs 14. The plates 12 and 13 and leaf springs 14 are preferably comparatively wide, although preferably slightly narrower

than the plate 10. There may be any number of the leaf springs 14 according to the length of the plate 10, and the plate 12 which is located at one end of the plate 10 has a tongue or extension 15 projecting beyond said end of the plate 10 in order to overlap the adjacent end portion of the adjoining plate 10, it being understood that the form plates or members are disposed end to end. The tongue or extension 15 will therefore aid in maintaining the plates 10 in alignment.

The flange 11 has small slots 16 therein adjacent to the plate 10, and said plate has slots 17 therein extending upwardly from its lower edge at suitable longitudinal points, for the purpose which will presently appear.

In the building of a concrete road or other surfacing structure, using the present form, one concrete slab or section 18 is produced in the usual manner, its sides or edges being defined by the usual side forms or rails (not shown). After the slab 18 has hardened sufficiently the plate 10 is disposed adjacent to the side or edge of the slab 18 along which the other slab 19 is to be produced, the form rail having been removed from the slab 18. The plate 10, or a series of them disposed end to end, is positioned so that the flange 11 overlaps the upper surface of the slab 18, with the convex surfaces of the springs 14 bearing against the side or edge of the slab, as seen in Figs. 1 and 3. This spaces the plate 10 from the slab 18. The slab 19 is then produced, and the plate serves as a form member to define the corresponding side or edge of said slab 19, the flange 11 being used to support a screed board or other implement used for striking off the surface of the concrete in finishing the slab 19. The flange 11 closes the space between the slabs, to prevent the concrete from running over into or falling down the space between the slabs, as well as assisting in holding the plate 10 in place during the building of the slab 19. The slots 17 are for the purpose of accommodating tie or dowel rods 20 that are used for tying together the slabs 18 and 19, said rods 20 extending across the space between the slabs.

After the concrete of the slab 19 has set sufficiently, and after the slab 19 has been edged along the upper edge of the plate 10, said plate 10 is removed from between the slabs.

slabs. The yielding action of the springs 14 will enable the plate 10 to be withdrawn from between the slabs without distorting, chipping or breaking the edges of the slabs, 5 which may still be green, inasmuch as the form is removed before the concrete has completely hardened. The springs or yielding spacers 14 thus permit the plate 10 to be moved slightly away from the slab 19 in 10 withdrawing the form.

The slots 16 enable a hook 21 to be used for withdrawing the form from between the slabs, said hook being engaged downwardly through one of the slots 16 under the flange 15 11, in order that the form may be lifted out of the slot, and, at the same time, the form may be shifted away from the slab 19, by bending the springs or spacers 14, toward the hardened slab 18 and away from 20 the green slab 19, in order that the form may be withdrawn without disturbing or injuring the slab 19.

The forms may be used for producing either longitudinal or transverse joints in 25 concrete roads, and the space between the slabs may be filled with a bituminous filler, concrete of a different color, or other suitable material, for making a water tight seal between the slabs, and the filler may also 30 serve as a traffic line extending longitudinally of the road between the opposite slabs.

Fig. 4 illustrates a modification, in that the plate 10' has the flange 11' at its upper edge and has the spring portion or spacer 35 14' as an integral part thereof, bent back from its lower edge below the flange 11'. The portion 14' is spaced from the plate 10' and extends upwardly to a point near but spaced from the flange 11'. The slots 17' 40 extend upwardly into the plate 10' and portion 14' through the bend between them, and the portion 14' may yield to enable the form to be withdrawn from between the slabs without injuring the green slab adjacent to 45 the plate 10'.

Having thus described the invention, what is claimed as new is:

1. A concrete form of the character described comprising a plate having a flange 50 at its upper edge to overlap a completed

concrete slab and having means below said flange for spacing said plate from said slab.

2. A concrete form of the character described comprising a plate having a flange extending to one side from its upper edge 55 to overlap a completed concrete slab, and having yieldable means below said flange for spacing said plate from said slab.

3. A concrete form of the character described comprising a plate having a flange 60 at its upper edge to overlap a completed concrete slab, and having a spring portion below said flange to bear against said slab and space said plate therefrom.

4. A concrete form of the character described comprising a plate of a height equal to the depth of a concrete slab and having a flange at its upper edge extending to one side to overlap said slab, and spacing means 65 below said flange for spacing said plate from 70 the slab.

5. A concrete form of the character described comprising a plate of a height equal to the depth of a concrete slab and having a flange at its upper edge extending to one 75 side to overlap said slab, and yieldable spacing means to be disposed between said plate and slab.

6. A concrete form of the character described comprising a plate having a flange 80 at its upper edge to overlap a completed concrete slab, and spacing means to be disposed between said slab and plate.

7. A concrete form of the character described comprising a plate having a flange 85 at its upper edge to overlap a completed concrete slab, said plate having a slot extending upwardly from its lower edge to accommodate a tie rod, and spacing means to be disposed between said plate and slab. 90

8. A concrete form of the character described comprising a plate having a flange at its upper edge to overlap a completed concrete slab, said flange having a slot adjacent to said plate for the engagement of 95 an implement to lift the plate, and means for spacing said plate from said slab.

In testimony whereof I hereunto affix my signature.

JOHN N. HELTZEL.
